UNITED STATES PATENT OFFICE.

HENRY C. NYE, OF SYRACUSE, NEW YORK, ASSIGNOR, BY DIRECT AND MESNE ASSIGNMENTS, TO THE NYE BOILER CLEANER COMPANY, OF SAME PLACE.

BOILER-CLEANER.

SPECIFICATION forming part of Letters Patent No. 450,974, dated April 21, 1891.

Application filed December 15, 1890. Serial No. 374,717. (No model.)

To all whom it may concern:

Be it known that I, HENRY C. NYE, of Syracuse, in the county of Onondaga, in the State of New York, have invented new and useful 5 Improvements in Boiler-Cleaners, of which the following, taken in connection with the accompanying drawings, is a full, clear, and exact description.

The purpose of this invention is to eliminate 10 the mineral substances from the feed-water entering the boiler and thus prevent incrustation of the latter; and to that end the invention consists, essentially, of one or more pans situated in the upper part of the interior 15 of the boiler, and the feed-water pipe having its discharge end in one end of said pan or pans, as hereinafter more fully described, and specifically set forth in the claim.

In the annexed drawings, Figure 1 is a side 20 view of a boiler provided with my invention, a portion of the boiler-shell being broken away to show the devices for eliminating the extraneous mineral substances from the feed-water. Fig. 2 is a transverse section on line 25 xx , Fig. 1. Fig. 3 is a detached vertical longitudinal section of the pans, with the feed-water pipe and blow-off pipe attached thereto, and Fig. 4 is an enlarged longitudinal section illustrating the operation of the apparatus.

30 Similar letters of reference indicate corresponding parts.

B represents the boiler, and cc the flues through which the products of combustion pass.

35 P and P' represent two open-topped pans, which are arranged end to end in one continuous plane and communicate with each other at their junction. Said pans are situated in the upper part or steam-space of the 40 boiler and extend lengthwise thereof.

In new boilers suitable supports for the pans may be applied to the boiler-shell, but for supporting the pans in boilers already in use I prefer to employ suitable metallic posts 45 or trestle tt , mounted on the top row of flues cc , and carrying upon their tops the aforesaid pans, as illustrated in Figs. 1 and 2 of the drawings. I incline the pans toward one end of the boiler and build across the interior of 50 the pans at or near their junction a dam b , which extends part way the height of the pan,

as shown in Fig. 3 of the drawings. The feed-water pipe a enters the boiler through the top thereof and has its discharge end in the elevated end of the pan P and terminated near 55 the bottom of the interior thereof, so as to be in a plane below the top of the dam b , and thus constantly submerged in the water which is retained in the pan by the aforesaid dam.

To the bottom of the opposite end or lower 60 end of the pan P' , I attach the blow-off pipe a' , which is extended through the boiler-shell and provided at the exterior thereof with the blow-off cock d .

The pan P constitutes a steam-trap, which 65 water-seals the discharge end of the feed-pipe, so as to prevent back-pressure of steam in said pipe. The other pan P' constitutes the precipitate collector, and the operation of said pans is as follows: In feeding water to 70 the boiler while generating steam, the water issuing from the feed-pipe agitates the water in the pan P , as represented in Fig. 4 of the drawings, and thereby prevents the impurities from precipitating in said pan. Neither 75 is the inflowing water retained in said pan a sufficient length of time to heat said water to the temperature which separates the impurities from the water. When it enters the pan P' , it becomes tranquil and attains a temper- 80 ature which causes the impurities to precipitate in this pan, while the pure water overflows the lower end of said pan and descends to the water-space of the boiler. Inasmuch as the pans are not subjected to the impinge- 85 ment of fire and are constantly enveloped in steam when the boiler is heated, the mineral substances gathered in said pans remain in a granular or amorphous state, and by opening the blow-off cock d said substances are 90 blown out of the pans and through the blow-off pipe a' by the pressure of the steam in the boiler.

I do not limit myself to any particular number of pans to be used in a boiler, inasmuch 95 as that depends on the length of the boiler, but in every case the pans are to be connected end to end and inclined toward one end of the boiler, as shown. It is also obvious that in a boiler of ordinary length a single 100 pan may be made of sufficient length to answer the purpose of my invention. The pans

are introduced into the boiler through the manhole thereof and are easily set upon their supports inside of the boiler and coupled together end to end. The form of the supports 5 of the pans depends somewhat on the style of boiler to which the pans are to be applied.

Having described my invention, what I claim as new, and desire to secure by Letters Patent, is—

- 10 The combination, with the boiler, of the precipitate-collecting pan P' and the steam-trap pan P , both open at the top, connected to-

gether and inclined as shown, the feed-pipe entering the upper end of the trap-pan, and the dam b , extending across one of said pans, 15 the latter so arranged that the water will flow into the boiler over the lower end of the pan P' , substantially as set forth.

In testimony whereof I have hereunto signed my name this 8th day of December, 1890.

HENRY C. NYE. [L. S.]
